ABSTRACT

A compartment having one open side and inner walls extending to opposite edges of said open side around the area to be refrigerated which inner walls define the walls of a first conduit for conducting refrigerated air from an inner inlet along one of said opposite edges of said open side to an inner discharge nozzle along the edge opposite thereto for forming a curtain of primary or refrigerated air across said open side between said nozzle and said inlet.

REFRIGERATED REACH-IN DISPLAY COMPARTMENT

A second conduit outwardly of said first conduit and heat insulated therefrom by intermediate walls conducts unrefrigerated or guard air around the area bounded by said inner walls from an outer inlet outwardly of said inner inlet and adjacent to the latter to an outer nozzle outwardly of and along said inner nozzle to discharge an outer curtain of guard air of higher temperature than said primary air across said open side.

Altitude-compensating dampers in said conduits are automatically actuatable by changes in the density of the ambient air at different elevations to maintain air distribution pressure within said conduits at elevations substantially above sea level.

Velocity-maintaining dampers within said conduits are automatically actuatable upon and by reason of the occurrence of unequal velocities of air within said first and second conduits for movement to different positions to reestablish the air velocities in the conduits approximately equal.

A refrigerated uninsulated heat transfer member in communication with the air within both conduits is movable to different positions across the reflective space within said first conduit to dehumidify said guard air.

Structure is also provided for moving the air within said conduits whereby a single air mover may be used in each compartment, and also structure is provided for drainage of melted ice on the inner ceiling wall of the area bounded by said inner walls upon defrosting.

BACKGROUND OF THE INVENTION

This is a continuation-in-part of U.S. Pat. application Ser. No. 214,702 filed Jan. 3, 1972, now abandoned.

The present invention relates to improvements in the type of refrigeration systems in which one of the sides of the area to be refrigerated is open.

Systems of this general type are shown in U.S. Pat. Nos. 2,862,369 and 3,397,631 of Dec. 2, 1958 and Aug. 20, 1968, respectively, U.S. Pat. No. 3,128,609 of Apr. 14, 1964 to S. Beckwith et al. and Hagen et al. 3,134,243 of May 26, 1964.

In these installations in which an inner curtain of refrigerated air, hereinafter referred to as a curtain of "primary" air, and an adjoining curtain of higher temperature, hereinafter referred to as a curtain of "guard" air, are projected across the open side of the compartment, it has been found that the air distribution along the discharge nozzles are arranged for lower elevations, is erratic and irregular at substantially higher elevations where air density is lower.

Also in such installations where the air of the guard curtain is ambient air of excessively high humidity frost-clogging of the cooling coils for cooling the primary air noticeably increases the defrosting requirements.

Furthermore, in the multiple-air-curtain installations employing primary and guard air, the velocity of the primary air becomes progressively slower than the velocity of the guard air following each defrosting of the cooling coils, whereas the velocity should preferably be substantially the same at all times to produce optimum results.

SUMMARY OF THE INVENTION

Generally the objects of the present invention are the provision of method and means in systems of the type hereinabove mentioned, for overcoming the objections above-described and others.

One specific object of the invention is the provision of a method and means in a system of the type hereinabove described for providing uniform air distribution 10 at the discharge nozzles at elevations where heretofore the distribution has been irregular and unsatisfactory due to the change in pressure characteristics of flow at higher elevations.

Another object is to provide a method and means in 15 a cooling system employing separate conduits for the primary and guard air for the curtain, for dehumidifying the guard air before it reaches the curtain for reducing the high requirements for defrosting the cooling coils.

An added object of the present invention is the provision of means for maintaining equal velocities of the air to the discharge nozzles or to maintain the movement of the air at predetermined different velocities.

A still further object is the provision of means in a 25 multiple conduit, multiple air-curtain arrangement in a compartment cooling structure of the type described, for effecting movement of the air in the conduits of a series of sections or compartments, in a more efficient manner than heretofore.

In addition to the foregoing, a still further object of the invention is the provision means for the removal of ice and moisture that may occur on the ceiling or in the upper portion of the compartment being refrigerated.

Other objects and advantages will appear in the description and drawings.

DESCRIPTION OF DRAWINGS

FIG. 1 is a simplified, perspective view of a cabinet 40 having two compartments, the shelves therein being omitted.

FIG. 2 is an enlarged, vertical cross-sectional view through one of the compartments in a cabinet.

FIG. 3 is a schematic view of the velocity control unit 45 indicated in FIG. 2.

FIG. 4 is a fragmentary enlarged cross-sectional view of a modification of a portion of the structure shown in FIG. 2.

FIG. 5 is a semi-diagrammatic fragmentary sectional view of a modification on the blower system only of FIG. 2.

FIG. 6 is an enlarged fragmentary cross-sectional view of a portion of FIG. 5.

FIG. 7 is a diagrammatic view of a modification of 55 the arrangement of FIG. 5 in a pair of sections as viewed at a right angle to FIG. 5.

FIG. 8 is a semi-diagrammatic, enlarged cross-sectional view along line 8—8 of FIG. 7.

FIG. 9 is a semi-diagrammatic view similar to FIG. 8 60 as viewed along line 9—9 of FIG. 7.

FIG. 10 is a diagrammatic view of one section, similar to FIG. 7, in which one blower is driven in an opposite direction to the other by a single motor.

FIG. 11 is a diagrammatic view at line 11—11 of FIG. 65 10.

FIG. 12 is a diagrammatic view at line 12—12 of FIG. 10.

FIG. 13 is a diagrammatic view similar to FIG. 10 in which separate motors drive the respective blowers in one section oppositely.

FIG. 14 is a semi-diagrammatic, cross-sectional view through one compartment, showing a modification in which a single blower of the propeller type circulates the air for a pair of contiguous layers of primary and guard air.

FIG. 15 is a semi-diagrammatic, cross-sectional view of a modification of the structure shown in FIG. 14.

FIGS. 16-18 each diagrammatically shows a different modification of the intermediate conduit wall at opposite sides of the blower or face shown in FIG. 15.

FIG. 19 is an enlarged, fragmentary cross-sectional view of a modified portion of FIG. 2.

FIG. 20 is a fragmentary elevational view of the structure shown in FIG. 19.

FIG. 21 is an elevational view of a further modification of the structure shown in FIGS. 19 and 20.

DESCRIPTION OF THE INVENTION

The compartment illustrated may be one compartment having opposite end walls, which are normally insulated, or it may be one of several in a row, in which case the framework within the cabinet may provide one set of air conduits for each compartment. FIG. 1 shows a pair of compartments with a partition separating them.

The details of construction, such as the provision of structural reinforcing and spacing members between walls defining the air conduits and other structural features are well known to those skilled in the art, are simplified or omitted in the interest of clarity.

FIG. 2 is a simplified semi-schematic, vertical cross-sectional view taken transversely through a compartment of FIG. 1 having an inner wall generally designated 1. Said wall 1 comprises a generally horizontally-extending inner ceiling or upper wall 2, a vertically extending inner rear wall 3 and a horizontally extending inner bottom wall 4. The front side of the compartment is open or is provided with an opening through which access to the interior of the compartment is had.

Walls 2, 3, 4 are not heat insulated, and are of material such as metal, having good heat conducting properties.

An intermediate wall generally designated 5 is spaced outwardly of the inner wall 1, and is insulated against transfer of heat. Said wall 5 comprises an upper generally horizontally extending wall 6 that may be parallel with wall 1 and in spaced, opposed relation thereto, a vertically extending wall 7 in parallel spaced opposed relation to wall 3, and a generally horizontally extending lower wall 8 in spaced opposed relation to wall 4.

The outer wall of the compartment, generally designated 9, is spaced outwardly of the intermediate wall 5, is insulated against transfer of heat, which wall includes an upper wall 10 in spaced opposed relation to wall 6, a vertically extending rear wall 11 in spaced opposed relation to wall 7, and a bottom wall 12 in spaced, opposed relation to wall 8.

The primary and guard air conduits extending around a cabinet from the open side may be divided by a frame member 13 (FIG. 1) so that one section of the conduits is at one side of the partition and another section at the other side. There may be any number of such sections in a cabinet, according to the length of the latter and the number of such frame members. Usually the dis-

tance between the ends of each section is approximately 4 to 12 feet, and the interior of the cabinet may include a partial or full partition 13' at each member 13. Thus the word "compartment" will be used to identify the area within a cabinet across one open side of which a pair of air curtains from a pair of discharge nozzles extend.

Walls 1 and 5 define opposite sides of an inner air conduit generally designated 15, and walls 5, 9 define opposite sides of an outer conduit generally designated 16.

The upper forward end of conduit or passageway 15 communicates with a horizontally elongated, downwardly directed discharge nozzle 17, while the upper forward end of conduit or passageway 16 communicates with a correspondingly elongated downwardly directed discharge nozzle 18. These nozzles extend substantially from end-to-end of each compartment and are parallel, with nozzle 18 alongside but slightly above nozzle 17. Said nozzles are of the type shown and described in U. S. Letters Patent 3,143,952 of Aug. 11, 1964 in which each nozzle comprises a plurality of parallel adjacent passageways. The passageways of nozzles 17, 18 extend convergently downwardly relative to each other to respectively form an inner curtain 19 and an outer curtain 20 obliquely meeting adjacent to the nozzles whereby the curtains will move contiguously downwardly in substantially parallel paths to enter inlets 21, 22 at the lower forward ends of conduits 15, 16.

The lower end of conduit 15 communicates with inlet 21, which is upwardly directed to receive the air of curtain 19 and the lower forward end of conduit 16 communicates with the inlet 22, which is upwardly directed to receive the air of curtain 20. Said inlets extend from end-to-end of the compartment, the nozzles 17, 18 defining the upper edge or side of the open side of the compartment, and inlets 21, 22 defining the lower edge or side of said open side.

Shelves, indicated in dot-dash lines, are normally provided within the compartment for supporting the products to be positioned therein. Such shelves do not project sufficiently far from the rear wall 3 to disturb the air curtains 19, 20.

Cooling coils 23 are positioned within the portion of conduit 15 that is below the bottom wall 4.

The air that is moved through the conduit 15 from the inlet and discharged from the nozzle 17 has been called "primary" air, being conditioned or refrigerated, while the air moved through conduit 16 has been called "guard" air, and the curtain 20 a "guard" curtain, as it is interposed between the atmospheric outside air and the curtain 19. It is common at times to provide means for forming an additional guard curtain outside the curtain 20, particularly where compartments may be at opposite sides of an aisle with their open sides facing each other. Insofar as the present invention is concerned the guard curtain and guard air is the curtain that is adjacent to the primary air. Whether one or more guard curtains is or are provided is immaterial.

The word "width" where used with respect to either conduit means the horizontal dimension in a section longitudinally of the compartment, while the word "depth" is the horizontal dimension at a right angle to the width.

As seen in FIG. 2 the propeller type air movers 24, 25 are respectively shown in the portions of conduits 15, 16 below the bottom wall 8.

A portion of the intermediate wall 7 that is between conduits 15, 16 comprises a dehumidifying plate 28 of uninsulated heat conductive material. This plate is parallel with wall 3 and is in alignment with an opening in the intermediate rear wall 7, forming a reflective space. A flexible diaphragm 29 around the edges of the plate connects with said wall 7 and closes the opening to leakage of air from one of the conduits to the other.

A plurality of bearings 30 (FIG. 2) secured to the inner wall 3 supports rods 31 that, in turn, are secured to plate 28, thereby carrying plate 28. Plate 28 may be moved to different positions toward or away from wall 3 by manually pushing or pulling rods 31 from within the compartment to increase or decrease the reflective space between wall 3 and plate 28. A set screw 32 threadedly extending through each bearing 30 will secure each rod 31, and consequently plate 28, in adjusted position.

Straight, vertically disposed, horizontally spaced heat conducting fins 33 or heat conducting pins 34 on the plate 28 spaced between adjacent pairs of fins 33 project into conduit 16.

By moving the plate 28 toward inner wall 3 the reflective space between the plate and wall 3 will be decreased. As this distance is decreased, the fins 33 or pins 34 will become colder, with corresponding dehumidification of the air in conduit 16. The plate 28 may be fixed in the adjusted position for obtaining the desired dehumidification of the air in the conduit 16. The result is a decrease in the frosting of coils 23, hence a decrease in the defrosting requirement, due to a reduction in the humidity of air in conduit 15 resulting from some air in curtain 20 becoming entrained with the air in curtain 19.

One or more dehumidifying plates may be employed in wall 7, which plates may be of the size found to be most effective for the humidity conditions and the size of the conduits.

When display cases of the type herein described, arranged to operate efficiently at or about sea level, are operated at several thousand feet elevation, the velocity of the jets at various points along the nozzles have been observed to be erratic and irregular. Such eccentricities cause uneven maintenance of temperature in the display case, whether it is of the type having two or more contiguous air curtains for ice cream and frozen foods or that having a single air curtain as is commonly employed for meat and delicatessen products.

It is believed that this results from a loss of distribution pressure, i.e., the pressure in the air curtain system is below the minimum required to assure even distribution of air velocity at all points along the jet nozzles because the air is less dense at the higher elevation. This problem may be solved by increasing the air flow in the curtain conduits at higher altitudes so as to increase the pressure in the system by the use of an altitude-compensating damper. Although the damper will first be described and is shown in conduit 15, it may be similarly utilized in conduit 16.

A damper plate 37 (FIG. 2) extends across the width of the compartment and may be positioned for movement projecting into conduit 15. The intermediate wall 7 may be formed with a recess 38 to receive said plate while a flexible expandable and contractible diaphragm 39 extends around the edges of the plate connecting it with the wall 7 to prevent leakage of air through opening 38.

A plurality of sets of rods 40 secured at one of their ends to plate 37 slidably extend into the recess 38 and through the rear wall 11. Said rods support the plate 37 for movement to different positions across the conduit

5 15. The rearwardly projecting ends of rods 40 are connected with a cross frame member 41, and between said member and wall 11 is a closed, horizontally expandable and contractible, sealed, closed bellows 42 enclosing air or gas.

10 15 A pair of legs 43 between rods 40 and at opposite sides of bellows 42 are rigid on wall 11 at one of their ends, and a cross bar 44 connects their opposite outer ends. Cross member 41 has bearings 45 through which legs 43 extend, hence member 44 slidably support legs 40.

15 A rod 46, secured at one end to cross member 41 extends through a bearing 47 and projects outwardly of cross bar 44.

20 25 A spring 48 around rod 46 is secured at its ends to cross member 41 and cross bar 44 and normally, at approximately sea level, and up to a predetermined, relatively low elevation the spring 48 will not be under stress and will yieldably maintain the plate 37 projecting into conduit 15 to restrict the flow of air through the latter. In effect damper 37 throttles conduit 15 at lower elevations.

25 30 At higher elevations, above said predetermined elevation, the expansion of air or gas contained within the bellows will result in automatically moving the plate 37 toward the opening or recess in the intermediate wall 7 thereby withdrawing it from and resulting in an increase in the quantity of air flow in conduit 15. The increased circulation causes an increase in pressure sufficient to maintain the distribution pressure to preserve even velocity distribution along the nozzle.

35 40 The provision of a set screw 49 in bearing 47 for engaging the rod 46 would enable releasably fixing the plate 37 stationary within the conduit 15 at any altitude, since the head of rod 46 is accessible for manually moving the plate to any desired position.

45 50 The plate 37 and bellows 42 or their equivalent constitutes a barometric damper responsive to variations in the density of the air at different altitudes to control the volume flow of air in the conduit and maintain sufficient distribution pressure.

55 60 In the modified form of the invention as seen in FIGS. 19, 20, a barometric control damper 175 is positioned in conduit 15 and a similar damper 176 is positioned in conduit 16. In the positions shown in FIG. 19 said dampers restrict the volumetric capacities of both conduits, at lower elevations, and each damper may extend substantially the full width of each compartment.

65 70 Walls 177, 178, which substantially correspond to walls 7, 11 are recessed at 179, 180 for retraction of dampers 175, 176 for increasing the volumetric capacities of conduits 15, 16 and thereby modifying the distribution pressures at the discharge nozzles.

75 80 A diaphragm 179', 180' around the open side of each recess 179, 180 may lock out the recesses from the air flow in conduits 15, 16.

85 90 Rods 181 extend through openings in wall 177, which openings may be provided with bushings for slidably supporting said rods, and said rods 181 also extend through sleeves 182 that are slidable in openings in wall 178.

95 The outer ends of rods 181 are connected by a cross member 183 outside wall 178, while the inner ends are

secured to and support damper 175. Sleeves 182 are secured to damper 176 at their inner ends, and are adjustably secured at their outer ends to rods 181 by set screws 184.

A head on the outer end of each sleeve is adapted to be manually grasped for adjusting the position of damper 176 relative to damper 175 and conduit 16.

Movement of the cross member 183 away from wall 178 will result in simultaneous movement of dampers 175, 176 in conduits 15, 16 to increase the volumetric capacities of the conduits 15, 16.

Conventional packing glands may be provided on rods 181 and sleeves 182 to preclude leakage of air through the openings in walls 177, 178 while permitting reciprocable movement of the rods 181 and sleeves 182.

An expandable and contractible, sealed bellows 185, similar to bellows 42, encloses gas and is positioned between wall 178 and cross member 183.

A pair of legs 186 at opposite sides of each bellows are rigid on wall 178 at one of their ends, and a cross bar 187 connects their opposite ends. Cross member 183 has bearings 188 through which legs 186 extend, and a rod 189 secured at one end to cross member 183 extends through a bearing 190 centrally between the ends of cross bar 187.

A spring 191 around rod 189 reacts between bearing 190 and cross member 183. This spring functions in the same manner as spring 48, to restrict movement of the dampers under the influence of the expansion of bellows 185 until a predetermined elevation above sea level is reached, such as, for example, 2,000 feet.

As seen in FIG. 20, several bellows and sets of rods as shown in FIG. 19 may be used on long dampers, or single bellows and sets of rods may be used on shorter ones, but their actions are the same.

From the foregoing it is apparent that the dampers 175, 176 may be manually positioned by manual manipulation of rods 189, a head 193 being on each rod for that purpose, and the dampers may be locked in that position by set screws 192. When the set screws 192 are loosened the movement of the dampers is automatic, to provide an increase in the volumetric capacities of the conduits at elevations above a predetermined elevation as the atmospheric air becomes more rarified.

In FIG. 21 the damper elements 195, 196 are in the form of horizontally elongated blades extending horizontally between the ends of a compartment, the damper 195 being in conduit 15 and damper 196 being in conduit 16.

Damper element 195 is secured along its longitudinally extending edge facing air flow to a horizontally extending shaft 197 that is journalized for rotation at its ends in bearings carried by the end walls of the compartment. Shaft 198 similarly supports the damper element 196 in conduit 16. One of the ends of shafts 197, 198 project outwardly of one of the end walls 199 of the compartment and arm 200 is secured to the projecting end of shaft 197 while a corresponding arm 201 is secured to the projecting end of shaft 198.

The outer ends of said arms are each slotted longitudinally thereof at 202 and a horizontally extending rod 203 extends transversely across the slots. A sleeve 205 adjustable on rod 203 longitudinally of the latter carries a pin 204 that extends through the slot 202 in arm 200. A sleeve 205' adjustable on rod 203 longitudinally of the latter carries a pin 204 that extends into

slot 202 in arm 200. A set screw 207 locks sleeve 205 to rod 203 in adjusted position of the sleeve on the rod and a set screw 207' similarly locks sleeve 205' in adjusted position on rod 203.

A bearing 208 between arms 200, 201 slidably supports rod 203 for horizontal reciprocable movement and one end of rod 203 is connected with a plate 209 on one end of bellows 210 that is carried on a bracket 211 secured to a wall of the display cabinet. Posts 212 on bracket 211 slidably support plate 209.

A collar 213 is adjustably secured on rod 203 between bearing 208 and arm 201 by a screw 214, and a spring 215 around rod 203 reacts between the bearing 208 and collar 213.

By the arrangement shown in FIG. 21, the walls separating the conduits are not recessed and the barometric actuating means for the damper is within the confines of the outwardly projected outline of an end of the cabinet, where they may be readily accessible.

The positions of the dampers may be adjusted relative to each other by adjusting sleeve 205 or 205' on rod 203 and the dampers may be locked in position in the conduits by set screw 216 in bearing 208. Also the dampers may be manually set by manipulating the head 217 on the end of rod 203 that is remote from the bellows.

Where independently actuated dampers are in conduits 15, 16, the problem of adjusting their positions relative to each other in the respective conduits is simple. In FIGS. 19-21 where a single bellows is adapted to actuate the dampers in both conduits, it is to be understood that the damper 176 in the outer conduit of the pair may be positioned to offer a greater percentage of resistance to the air in conduit 16 than the damper 175 offers to the air in conduit 15. Provision for this difference has been made as herebefore described.

In a compartment under refrigeration, the primary air stream is the one that carries the refrigeration effect from the coil system. As slight leakage occurs across the layer of guard air at the curtain, some moisture passes to the primary air and is collected as frost on the refrigeration coils in the primary air circuit. This frosting and icing of the coils adds restriction to the air flow resulting in reduced velocity of the primary air. If the primary air is operated at a temperature which does not cause frosting, the restriction is reduced, but a coil which is merely dehumidifying has a resistance of approximately 30 to 40 percent over a dry coil in ordinary air conditioning. Thus, unfrozen moisture with an unrestricted coil may result in a decreased velocity of the primary air.

In the present instance sensors of an electrical thermal anemometer R_p and R_c , FIGS. 2, 3, are respectively positioned in the primary air stream in conduit 15, and in the guard air stream in conduit 16. These sensors are in a wheatstone bridge generally designated 54 (FIG. 3), the sensors being of the resistance-bulb type. Variation in the velocity of air passing over the resistance bulb will cause a variation in its resistance, a decreasing velocity being reflected in an increased resistance and vice versa.

In the wheatstone bridge (FIG. 3), R_1 and R_2 are fixed resistances, and R_3 is essentially a fixed resistance, but is shown as adjustable for convenience purposes of adjustment and calibration. R_4 and R_c are connected in series to form the resistance in the lower lefthand side of the bridge.

R_3 is an adjustable resistance and is in series with R_p to form the resistance in the upper lefthand side of the bridge. The symbols "P" and "G" indicate "primary" and "guard" air positions for the bulbs.

It should be realized that there is some variation in the resistance in the bulbs R_p and R_g , but this may be cared for at the time adjustment is made.

A damper 55 in conduit 15 is connected by suitable linkage 56 with a damper actuating motor 57 which motor, in turn, may be controlled by a manual manipulation of a conventional remote potentiometer controller 57' for positioning damper 55 for the desired velocity of the primary air, although there are instances where a fine adjustment is not essential.

Once the velocity of the primary air has been established, R_3 plus R_p will be a general control resistance, and balance in the wheatstone bridge circuit must be achieved by variation of the air flow in the guard conduit until the resistance of R_g plus R_4 equals the resistance of R_p plus R_3 . Assuming the guard air is moving faster than the primary air, the resistance R_g will be relatively low, thus an imbalance will occur between points A, B of the wheatstone bridge. This imbalance in the bridge will be transmitted to a conventional electronic amplifier and controller 59. The unbalanced output from the wheatstone bridge is amplified electronically to actuate a solenoid switch in the controller 59 which causes the reversible motor 60 connected with damper 61 in the guard air conduit to throttle until the resistance in R_g builds sufficiently to balance the wheatstone bridge.

If the velocity of the guard air is less than that of the primary air, a signal of the opposite direction will occur, which, when amplified, will cause a second solenoid switching device in the controller 59 for actuating motor 60 in an opposite direction for moving the damper 61 to a more open position for balancing the velocity in the two conduits.

In FIG. 3, current is shown as being supplied from a DC source, which is the simplest and preferred manner, although it is possible to operate the wheatstone bridge with an AC current. The bridge must then be constructed with correct resistances and inductances to balance the alternating bridge circuit. In the case of AC current, the impedance is the total opposition offered by a circuit to the flow of current, it being the combined effect of the resistance and the reactance of a circuit.

The damper motors 57, 60 may be conventional 24 volt AC reversible motors with dual windings, and the transformers are normally included in the controllers 57', 59. Said motors are geared motors to move very slowly, and motor 57 is the same type of motor as motor 59 except that it would not be under the electronic control of the wheatstone bridge output.

By increasing the resistance at R_3 by the movement of slide wire 62, the resistance $R_p + R_3$ is increased thereby increasing the resistance in the primary control circuit, which would have the same effect as a decrease in the velocity of the air over sensor R_p . Thus damper 61 must be moved to reduce the velocity in conduit 16, thereby resulting in an increased resistance in R_g to balance the bridge. The decreased velocity effect on bulb R_g actually offsets the effect of adjusting the slide wire 62.

It is accordingly seen that, to reduce the guard air velocity in conduit 16, add resistance at R_3 , and to in-

crease the air velocity in conduit 16, reduce the resistance at R_3 .

The velocity of the primary air at the discharge nozzle 17 is established by measurement with a proper velocity anemometer. With air in the primary and guard air conduits at different temperatures, the temperature effect for differential resistance between R_g and R_p may be adjusted by R_4 or R_3 until the guard air is flowing at the same velocity as the primary air. 10 Thereafter the guard air will track the primary air for equal velocity, or for differential velocity if so set.

Differential velocity between the guard and primary air results in a mixing of the air of curtains 19, 20 (FIG. 2) which increases the refrigeration load.

The electronic amplifiers and controllers used for ordinary air conditioning are readily adaptable for the type of signal received from the wheatstone bridge and the dampers are also conventional.

It is obvious that the system will operate when the primary air is heated and with the compartment under heating rather than refrigeration.

During operation of the system, there are conditions in which moisture will condense on the inner ceiling wall 2 and ice will form. When defrosted, this moisture may drop onto the products within the compartment.

To overcome this objection, the upper inner wall 2 is inclined downwardly from the nozzles at a slant sufficient to cause the moisture to flow rearwardly by gravity, and a horizontally extending trough 67 is removably positioned at the upper rear corner to receive the water. The bottom of the trough is inclined downwardly to one or more drain pipes 68 that, in turn, extend downwardly across duct 15 and to rear wall 11, and then in conduit 16 to the lower end of the latter and through the bottom of the compartment.

A solenoid actuated valve 69 in drain pipe 68 adjacent its lower end is automatically opened when the system is defrosted, and closed after defrosting, while a goose-neck trap 70 between valve 69 and outside the compartment prevents ingress of air when valve 69 is open. As many drain pipes may be provided as are found to be necessary. A heating element 71 may be in the bottom of trough 67 actuatable upon defrosting the system to melt ice in the trough.

As an alternative, a trough 72 (FIG. 4) may be removably positioned in the same place as trough 67. This trough is supported on a shelf 73 from which it is readily removable when containing ice, and replaced by an empty trough.

In the modified form of the invention shown in FIG. 5, the same numerals will be used to identify the structure that is the same as in FIG. 2.

Instead of using air movers 24, 25, conventional tangential air movers 80, 81 are respectively positioned within conduits 15, 16 at the junctures between the upper and rear walls defining the upper substantially right angle turns of the conduits (FIG. 5). Tangential blowers are sometimes called right angle blowers, each comprising an annular row of horizontally elongated blades 82 (FIG. 6) that may extend approximately the full width of each section. The blades of each blower are supported around a shaft 83 that, in turn, is driven by a motor 84 connected with one end of each shaft. Thus a plurality of said blowers in axial alignment, with one or more in the conduits of each section may be driven by a motor positioned outside of one end of the section or by one interposed between axially aligned

blowers in adjacent sections. The air in the conduit is driven around an arcuate path around the corner in each conduit from the inlet side to the outlet side and to nozzles 17, 18. If desired, conduit 16 may be tapped for cooling air conducted to the motors for cooling the latter, in a manner later illustrated.

FIG. 7 diagrammatically shows the arrangement in which a pair of coaxial tangential blowers are in an adjacent pair of sections in a cabinet. The primary and guard air in each section is moved by one of said coaxial pairs, requiring only one motor for the blowers of both pairs.

One of the adjacent sections is generally designated 91, and the other 92, similar sections are indicated in FIG. 1. The primary air conduit in each section is designated 93 (FIG. 7), and the guard air conduit 94. A vertical partition wall 95 in the upper corner of the primary air conduit 93 divides the conduits. Walls 96, 97 (FIG. 8) spaced from the corner at opposite sides thereof extend from the partition 95 to one of the end walls of the section and across approximately half of the primary air conduit in the section.

A horizontally-extending tangential blower 98 is supported for rotation about its longitudinal axis in suitable bearings in the corner portion of the primary air conduit between the walls 96, 97. An opening 99 (FIG. 8) is formed in the intermediate insulated wall 7' of the section above the wall 96 and adjacent to the lower side of blower 98, and a wall 100 extends across the guard air conduit 94 along the upper edge of said opening. This wall 100 extends from end-to-end of the section, hence all of the guard air is directed through opening 99 to the blower 98.

The same numerals are used to identify the walls of the conduits and other structure common to the different examples in FIGS. 5-10 except that they may be primed.

The wall 97 at the other end of the partition 95 is in the upper, generally horizontally-extending, portion of the primary or inner air conduit and is spaced in said portion from the blower. An opening 101 in the upper portion of the intermediate wall 7 opens into the main unpartitioned length of conduit 94 for movement of the guard air to the discharge nozzle 18.

From this it is seen that the guard air ascending the guard air conduit 94 will all pass through opening 99 to the tangential blower 98 and will be driven into the upper portion of conduit to the nozzle 18, the partition 95 terminating at its ends adjacent the upper corner so that the movement of the air delivered to and discharged from the conduit 93 will only be restricted at the upper corner of each compartment.

The second tangential blower 102 (FIGS. 7, 9) is coaxial with blower 98 and is preferably on the same shaft. This blower extends across the portion of the primary air conduit 93 that is not blocked by wall 96 (FIG. 9).

As illustrated in FIG. 7, a motor 105 may drive all of the coaxially aligned blowers in the pair of sections at opposite sides of the motor, the walls 106 adjacent sections at opposite sides of the motor providing a space for the motor that is isolated from the conduits except for ducts 107 and 108 that are tapped into the portions of the guard air conduit at the outlet side of the guard air conduit to conduct and move cooling air across the motor, and ducts 109, 110 return the air to the guard air conduits at the inlet side of the blowers. This insures

a constant cooling of the motors by the guard air where as heretofore the motors for driving the primary air were positioned within the primary air duct, thereby increasing the cost of cooling the compartments.

The inner wall 1' of the compartments, or sections, are preferably heat insulated along portion 112 (FIG. 8) in which each blower 98 is positioned to reduce transfer of heat from the guard air to the interior of the compartment, although any cooling of the guard air at the corner, by conduction, from the primary air, will function to cool the motor 105.

Diagonally extending rows of horizontally extending, transversely curved, turning vanes 113 (FIG. 8) extend across the portion 114 of the guard air conduit between the inlet 99 and outlet 101, and at the inlet and outlet, to guide the air past the turns to and from blower 98.

In the foregoing arrangement, the motor 105 will rotate all of the axially aligned blowers in the same direction, and one motor will take the place of several propeller type fans where a motor-driven fan is in each section.

In certain instances it may be desirable to simplify the relatively tortuous passage of air in the portion 114 of the guard air conduit as shown in FIG. 8.

FIGS. 10, 11, 12 illustrate one arrangement for accomplishing this result and FIG. 9, 10, 11 show another. In each example the blower and conduit arrangement is the same as shown in FIG. 10, 11.

In FIG. 10 one section is shown in which coaxial, tangential blowers 122, 123 are used, the blower 122 being for guard air and the blower 123 for primary air.

In this instance in the primary air conduit, spaced opposed partitions 124 (FIG. 10) provide a space 125 between the blowers 122, 123 in which motor 126 is positioned and which is connected by a pair of conventional drive chains, belts or gears with the shafts of blowers 122, 123 respectively to rotate the blowers in opposite directions. Walls 127, 128 extending respectively approximately at right angles to the rear outer wall 11' and from the upper outer wall 10' at the upper corner (FIGS. 11, 12) to meeting relation closing the guard air conduit at the corner. An inlet opening 130 in the intermediate wall 7' below wall 130 at the side of the partition in which blower 122 is positioned passes the guard air to blower 122. Outlet opening 131 in intermediate wall 6' is above blower 122 at the same side of partition 124 as walls 127, 128 and the blower 122 is in the same position as blower 123.

By this structure only one pair of turns at vanes 135 is required instead of the four shown in FIG. 8, but the blowers rotate in opposite directions.

The guard air conduit is tapped at the discharge side of the blower by a duct 138 to provide cooling air to motor 126, and a duct 137 conducts the cooling air back into the conduit 94 at the inlet side of the blower.

FIG. 13 shows the same corner arrangement for the blowers, except that a single partition 139 is used, and motors 140, 141 are respectively connected with the blowers 143, 142 that are respectively at opposite sides of the partition, one motor 140 driving the blower 143 in the same direction as blower 123 is driven, while the motor 141 drives the blower 142 in conduit 94 in the same direction as blower 122. In this arrangement a duct system 144 taps the guard air conduit to deliver cooling air from the guard air conduit to motors 140 and 141 for cooling the latter, while a duct 145 returns the air to the inlet side of blower 142.

While the preferred form would employ a separate motor for the blowers in the primary and guard air conduits, without dividing the conduits and diverting the air in one conduit, as disclosed in FIG. 6 the arrangement shown in FIGS. 7-12 has advantages over conventional systems in some instances. Also, the air flow control and dehumidifier in the guard air stream, and other structural features, are improvements in any air moving arrangement.

In the modifications shown in FIGS. 14-18, the flow control and dehydrating means employed in FIGS. 2-4 may remain the same, including the employment of the separate primary air and guard air conduits and their separate discharge nozzles and intake openings.

Within the top part of the cabinet the intermediate 15 wall 145 between the primary air conduit 146 and the guard air conduit 147 is formed with a gap within which motor 148 and blower 149 are positioned, the blower in this instance being the propeller fan type with the blades adapted to extend across the distance between 20 the outermost and innermost upper walls of the cabinet, and guide walls may extend convergently from the end walls of the compartment toward the blower to guide the air in both conduits to the blower fan for movement therewith.

Cooling coils 150 positioned within the upper portion of the primary air conduit 146 between the fan 149 and the discharge nozzle 151 cool the primary air that is discharged to form the inner layer of the air curtain, while the guard air is discharged from nozzle 152.

In FIG. 15, at the intake side of the fan and at the opposite discharge side, the latter being the side toward the discharge nozzles, a pair of generally horizontally-disposed plates 154, 155 are positioned, the plate 154 being at the intake side of the blower and the plate 155 being at the discharge side.

These plates are horizontal extensions of the intermediate wall between the primary and guard air conduits, and extend to opposite sides of the fan or blower 149.

In FIG. 16, plates 156, 157 are similar to plates 154, 40 155 with plate 156 disposed horizontally (FIG. 16), and while the plate 157 at the discharge side of the blower may have its edge 158 that is remote from the blower also horizontal, the plate is twisted about an extension of the axis of the fan so the edge 159 adjacent the blower is tilted in the direction of rotation of the blades of the fan. Thus at one side of the axis, edge 159 extends below the plane in which edge 158 is positioned, while the edge 159 at the other side of the axis is above said plane.

In FIG. 17 plates 160, 161 similar to plates 156, 157 are shown at the inlet and discharge sides of the fan, but in this case the plate 160 at the inlet side has the edge 162 remote from the fan horizontal, and the edge 163 adjacent the fan tilted oppositely to the direction of movement of the fan blades, while plate 161 is horizontal.

In FIG. 18, plate 164 at the inlet side of the fan is in the same position of plate 160 while plate 165 at the discharge side is in the position of plate 157.

The results in each instance are similar and directed to the same end of straightening the tendency of the body of air to swirl in the direction of rotation of the fan after leaving the fan.

It is to be understood that the cooling coil 150 may be positioned in the rear or bottom portion of conduit 146 and that the position of the fan or blower 149 is not

restricted to the upper portions of conduits 146, 147.

We claim:

1. The method of temperature conditioning air within a predetermined enclosed area having an access opening in one side but otherwise enclosed, comprising the steps of:

a. circulating in the same direction an inner and outer layer of air respectively in adjacent, parallel, endless inner and outer paths extending around said area and across said opening with said inner layer adjacent said area and the outer layer outwardly thereof relative to said area with said inner and outer paths and the air therein separated from each other along the lengths extending to and from said opening and with the portion of the inner layer extending across said opening in engagement with the air within said area and with the portion of the outer layer adjacent thereto, whereby said portions provide adjacent curtains extending between the ambient air and the air within said area;

b. temperature conditioning the air of said inner layer to a temperature different from that of said ambient air whereby air within said area will be similarly conditioned and said portion of said outer layer will guard said inner layer against intrusion by said ambient air;

c. applying a constant, uniform moving force to the air in said inner and outer paths for circulating them in said paths in the same direction with said inner and outer paths each having a predetermined volumetric capacity for producing predetermined distribution pressures at the points of discharge of said inner layer and said outer layer from said inner and outer paths across said opening when said area is at sea level;

d. increasing the volumetric capacity of said inner path upon a predetermined increase in the rarity of the atmosphere at higher elevations for maintaining an efficient distribution pressure at said higher elevations at said uniform moving force.

2. In the method as defined in claim 1:

e. controlling the volumetric capacities of said inner and outer paths at different predetermined elevations of said area above sea level without changing said uniform force by sufficiency increasing the volumetric capacities of said paths to flow of air therethrough to maintain efficient distribution pressure at said outlets.

3. In the method as defined in claim 2:

f. said step of increasing the volumetric capacities of said paths being effected by enlargement of said paths to passage of air therethrough under the influence of the expansive force of a gas enclosed at sea level.

4. The method of temperature conditioning air within a predetermined enclosed area having an access opening in one side but otherwise enclosed, comprising the steps of:

a. circulation in the same direction an inner and outer layer of air respectively in adjacent, parallel, endless inner and outer paths extending around said area and across said opening with said inner layer adjacent said area and the outer layer outwardly thereof relative to said area with said inner and outer paths and the air therein separated from each other along the lengths extending to and from said opening and with the portion of the inner layer

- extending across said opening in engagement with the air within said area and with the portion of the outer layer adjacent thereto, whereby said portions provide adjacent curtains extending between the ambient air and the air within said area;
- b. temperature conditioning the air of said inner layer to a temperature different from that of said ambient air whereby air within said area will be similarly conditioned and said portion of said outer layer will guard said inner layer against intrusion by said ambient air;
- c. the conditioning of said air being by refrigeration thereof within said path prior to the formation of said curtain;
- d. controlling the velocity of the air in said inner and outer paths extending to said curtain relative to each other to provide a predetermined velocity within each path by developing within each path forces responsive to changes from said predetermined velocity and applying said forces to oppositely movable path restrictors in said paths restricting or opening said paths effecting restoration to said predetermined velocity of air in said inner and outer passageway according to character of the variation.
5. An apparatus for conditioning a body of air within an enclosed area provided with an access opening in one side for insertion of objects therethrough into said area from ambient atmospheric air outside said area for withdrawal therefrom, said apparatus including an inner and an outer conduit extending around said area terminating in a discharge outlet along one edge of said opening and an inlet along the opposite edge facing said discharge outlet, said inner conduit having an uninsulated wall of heat transfer material in heat transfer relation to the air within said area, and said outer conduit being adjacent and outwardly of said inner conduit relative to said area:
- a. air moving means for simultaneously circulating air in inner and outer endless paths extending through said inner and outer conduits and across said opening from said discharge outlets to said inlets, providing a curtain of air across said opening in the form of inner and outer layers respectively in continuation of the air of said inner and outer conduit;
- b. air cooling means for cooling the air moving through said inner conduit for cooling the air within said area through conduction through said uninsulated wall; and
- c. control means for automatically controlling the velocity of the air in said paths at predetermined velocities independently of said air moving means.
6. In an apparatus as defined in claim 5:
- d. said control means being velocity-responsive electrical resistance elements respectively positioned within said conduits and velocity controlling dampers in an electrical circuit with said elements respectively supported within each conduit and operatively connected with electrically actuated means for moving said dampers to positions to automatically effect restoration of the desired predetermined velocities upon variations therefrom occurring in said conduits.
7. In apparatus as defined in claim 5:
- d. heat transfer means within said inner conduit in heat exchange relation with the cold air in said inner conduit extending into said outer conduit in

- heat exchange relation with the air in said outer conduit for dehydrating the air in said outer conduit.
8. In apparatus as defined in claim 5:
- d. pressure control means within at least one of said conduits movable to different positions therein for varying the distribution pressure of air at its discharge nozzle.
9. In apparatus as defined in claim 5:
- d. pressure control means respectively within said inner path and said outer path movable to different positions therein for varying the distribution pressure in said inner and outer conduits at their discharge outlets upon a predetermined increase in the rarity of the atmospheric air at different elevations above sea level, whereby efficient distribution pressures at said outlets will be maintained at said predetermined elevations.
10. In apparatus as defined in claim 9:
- e. said pressure control means including an expandable member enclosing a body of gas expandable at said predetermined altitudes, and means within said conduits restricting passage of air through said conduits to a predetermined volumetric amount connected with said expandable member for movement to less restrictive positions for increasing the volumetric capacities of said paths to passage of air therethrough for thereby maintaining efficient distribution pressures of air at said outlets.
11. An apparatus for conditioning a body of air within an enclosed area provided with an access opening in one side for insertion of objects therethrough into said area from ambient atmospheric air outside said area and for withdrawal therefrom, said apparatus including an inner and an outer conduit extending around said area terminating in a discharge outlet along one edge of said opening and an inlet along the opposite edge facing said discharge outlet, said inner conduit having an uninsulated wall of heat transfer material in heat transfer relation to the air within said area, and said outer conduit being adjacent and outwardly of said inner conduit relative to said area:
- a. air moving means for simultaneously circulating air in inner and outer endless paths extending through said inner and outer conduits and across said opening from said discharge outlets to said inlets, providing a curtain of air across said opening in the form of inner and outer layers respectively in continuation of the air of said inner and outer conduit;
- b. air cooling means for cooling the air moving through said inner conduit for cooling the air within said area through conduction through said uninsulated wall;
- c. dehydrating means positioned within said outer conduit for dehydrating the air moving therein to said discharge outlets;
- d. said dehydrating means comprising heat transfer means in heat exchange relation with the air in said inner conduit extending into said outer conduit in heat exchange relative with the air in the latter.
12. In apparatus as defined in claim 11:
- e. a wall of heat insulating material defining a wall common to and separating said inner conduit from said outer conduit;
- f. said heat transfer means including a plate of heat transfer material within said inner conduit in spaced opposed relation to side of said inner con-

duit in heat exchange relation to the air within said area providing a reflective space between said plate and said side of said inner conduit, and heat exchange members integral with said plate extending into said outer conduit for passage of the air within the latter therewith and condensation of moisture in said last mentioned air.

13. An apparatus for conditioning a body of air within an enclosed area provided with an access opening in one side for insertion of objects therethrough into said area from ambient atmospheric air outside said area and for withdrawal therefrom, said apparatus including an inner and an outer conduit extending around said area terminating in a discharge outlet along one edge of said opening and an inlet along the opposite edge facing said discharge outlet, said inner conduit having an uninsulated wall of heat transfer material in heat transfer relation to the air within said area, and said outer conduit being adjacent and outwardly of said inner conduit relative to said area:

- a. air moving means for simultaneously circulating the air in inner and outer endless paths extending through said inner and outer conduits and across said opening from said discharge outlets to said inlets, providing a curtain of air across said opening in the form of inner and outer layers respectively in continuation of the air of said inner and outer conduit;
- b. air cooling means for cooling the air moving through said inner conduit for cooling the air within said area through conduction through said uninsulated wall;
- c. control means for automatically controlling the velocity of the air in said paths at predetermined velocities independently of said air moving means;
- d. pressure control means respectively within said inner path and said outer path movable to different positions therein for varying the distribution pressure in said inner and outer conduits at their discharge outlets upon a predetermined increase in the rarity of the atmospheric air at different elevations above sea level, whereby efficient distribution pressures at said outlets will be maintained at said predetermined elevations.

14. An apparatus for conditioning a body of air within an enclosed area provided with an access opening in one side for insertion of objects therethrough into said area from ambient atmospheric air outside said area and for withdrawal therefrom, said apparatus including an inner and an outer conduit extending around said area terminating in a discharge outlet along one edge of said opening and an inlet along the opposite edge facing said discharge outlet, said inner conduit having an uninsulated wall of heat transfer material in heat transfer relation to the air within said area, and said outer conduit being adjacent and outwardly of said inner conduit relative to said area:

- a. air moving means for simultaneously circulating air in inner and outer endless paths extending through said inner and outer conduits and across said opening from said discharge outlets to said inlets, providing a curtain of air across said opening in the form of inner and outer layers respectively in continuation of the air of said inner and outer conduit;
- b. air cooling means for cooling the air moving through said inner conduit for cooling the air

within said area through conduction through said uninsulated wall;

- c. pressure control means respectively within said inner path and said outer path movable to different positions therein for varying the distribution pressure in said inner and outer conduits at their discharge outlets upon a predetermined increase in the rarity of the atmospheric air at different elevations above sea level, whereby efficient distribution pressures at said outlets will be maintained at said predetermined elevations;
- d. said pressure control means including an expandable member enclosing a body of gas expandable at said predetermined altitudes, and means within said conduits restricting passage of air through said conduits to a predetermined volumetric amount connected with said expandable member for movement to less restrictive positions for increasing the volumetric capacities of said paths to passage of air therethrough for thereby maintaining efficient distribution pressures of air at said outlets.

15. The method of temperature conditioning air within a predetermined enclosed area having an access opening in one side but otherwise enclosed, comprising the steps of:

- a. circulation in the same direction an inner and outer layer of air respectively in adjacent, parallel, endless inner and outer paths extending around said area and across said opening with said inner layer adjacent said area and the outer layer outwardly thereof relative to said area with said inner and outer paths and the air therein separated from each other along the lengths extending to and from said opening and with the portion of the inner layer extending across said opening in engagement with the air within said area and with the portion of the outer layer adjacent thereto, whereby said portions provide adjacent curtains extending between the ambient air and the air within said area;
- b. temperature conditioning the air of said inner layer to a temperature different from that of said ambient air whereby air within said area will be similarly conditioned and said portion of said outer layer will guard said inner layer against intrusion by said ambient air;
- c. the conditioning of said air being by refrigeration thereof within said path prior to the formation of said curtain;
- d. removing moisture from the air of said outer layer by moving it across a heat conductor between said inner and outer paths in heat exchange relation with the air in both paths at a restricted location therealong for condensing excess moisture in the air of said outer layer at said location.

16. In the method as defined in claim 19:

- e. varying the degree of cooling of the air in said outer path at said location by varying the position of said heat conductor toward and away from the side of the inner path opposite thereto, thereby varying the conductance of the space between said heat conductor and said last mentioned side of said path.

17. In a refrigerated display compartment having a ceiling wall bottom wall, opposed lateral walls and a vertically extending rear wall defining the bounds of a storage space for products, and an access opening at

the front opposite said rear wall for insertion and removal of such products into and out of said space:

- a. a continuous inner conduit for air extending across said ceiling, rear and bottom walls with said walls being uninsulated and forming one side of said inner conduit, and an outer continuous conduit for air coextensive with said inner conduit adjoining and positioned outwardly of said inner conduit relative to said storage space, said inner and outer conduits having outlet openings at one of their ends 10 at one side of said access opening, and inlet openings at their opposite ends at the side of said access opening opposite said one side of the latter with said outlet openings facing said inlet openings to provide an inner and outer curtain of air flowing 15 across said access opening, from said outlet openings to said inlet openings upon movement of air in said conduits from said inlet openings to said outlet openings;
- b. a discharge nozzle in the outlet of each conduit 20 having means within each for directing the air discharge therefrom in contiguous curtains extending from said nozzles to said inlet openings;

c. said conduits having an intermediate wall common to both conduits spaced outwardly of said ceiling, bottom and rear wall having terminal ends at said inlet openings and said outlet openings; refrigerating means within said inner conduit for cooling the air moving therethrough to said outlets, and a single motor-driven, propeller, fan-type blower having blades extending across said inner and outer conduits between opposite terminal ends of the latter for simultaneously moving the air in said conduits from their inlet openings to their outlet openings for forming said curtains, and a gap in said intermediate wall for rotation of said blades in a plane normal to the lengths of said conduits.

18. In a display compartment as defined in claim 17:
- e. said intermediate wall including a portion thereof adjacent one of the sides of said blower supported in a position for counteracting the tendency of the air moved by said blades to said discharge nozzles to swirl in the direction of rotation of said blades after leaving the latter.
